UNITED STATES PATENT OFFICE

GUSTAV J. SENGBUSCH, OF MILWAUKEE, WISCONSIN

WRITING PEN

Application filed March 16, 1932. Serial No. 599,072.

This invention relates to writing pens and may be applied to the more or less common type of writing pen in which the pen point is removable from the holder, although the invention is particularly designed and herein disclosed in connection with a writing pen of the type disclosed in my Patent No. 1,767,189, granted June 24, 1930.

The objects of the invention are to provide improved means for removably securing a pen point in place in a pen holder; to provide means for removably mounting a feed bar and pen point in a pen holder of the type disclosed in my said patent; and to provide improved means for the purpose mentioned which will be simple, durable, and highly effective for the said purpose. Other objects and advantages will be understood by reference to the following specification and accompanying drawing in which a writing pen embodying a selected form of the invention is illustrated.

In the drawing, Fig. 1 is a plan of the writing end of a pen holder in which a pen point is mounted.

Fig. 2 is a section on the line 2—2 of Fig. 1.

Fig. 3 is a section on the line 3—3 of Fig. 2, and

Fig. 4 is a perspective illustrating the component parts of the improved structure separated from each other.

Referring now to the drawing, a pen holder is shown at 5, and this pen holder includes an outer covering 6 which may be of hard rubber, bakelite, pyroxylin, or other desired material molded on a core 7 of wood to which a metallic sleeve 8 is secured at one end. As shown in Fig. 2, the metallic sleeve 8 constitutes a reinforcing sleeve for the hollow, pen point receiving end of the pen holder.

A pen point 9 and a feed bar 10 are disposed in cooperative relation so that the rearward portion 11 of the feed bar constitutes a filler bar in the hollow end of the pen holder and fits under the rearward portion 12 of the

pen point 9 to form therewith a shank adapted to fit within the hollow end of the sleeve 8 of the pen holder. For insuring proper positioning of the pen point 9 and feed bar 10 longitudinally of each other, the feed bar 10 is provided with an indentation 13 for receiving the projection 14 on the under side of the pen point 9 which is formed by indenting a portion thereof as clearly shown in Fig. 2.

For removably holding the pen point and feed bar in operative position in the hollow end of the pen holder, a metallic spring element 15 is provided. This spring element may conveniently be formed of a length of spring wire doubled upon itself to form a double wire element as clearly shown in Fig. 4, the front end of the spring element being thus formed into a slightly offset loop 16. The main body portion of the spring element may be termed a wing portion, and it is provided at its rear end with a laterally extending stem portion 17 which is adapted to extend into an opening 18 which extends transversely through the rear end portion of the feed bar 10. On its under side, the feed bar is provided with a longitudinally extending groove 19 for receiving the wing portion of the spring as clearly shown in Figs. 2 and 3. The spring may fit the opening 18 so as to be readily removable therefrom so that it may conveniently be replaced in the event that it loses its resiliency, and it is preferably made of or plated with such metal as will resist corrosion by ink.

By inspection of Fig. 2, it will be seen that when the pen point and feed bar (to which the spring 15 is secured) are inserted into the hollow end of the pen holder, the spring 15 will bear against the inside of the hollow end of the pen holder to removably hold the parts in assembled relation. If desired, the reinforcing sleeve 8 may be slightly counterbored as indicated at 20 to provide a stop shoulder 21 for limiting the extent to which the pen point will normally

ly be inserted. However, because of the conventional taper of the pen point, the provision of a stop shoulder such as just referred to is not necessary since the enlarged, transverse dimension of the pen point will serve to limit the extent to which the pen point may be inserted.

In accordance with the disclosure of my said patent, the outer or forward end portion of the feed bar 10 is provided with a plurality of narrow slots 21 which constitute reservoirs for holding a supply of ink or other writing fluid which is obtained by simply dipping the pen in a supply of ink in the conventional manner.

Changes may be made in the described structure without departing from the spirit of the invention, the scope of which should be determined by reference to the following claims which should be construed as broadly as possible consistent with the state of the art.

I claim as my invention:—

1. In a pen of the class described, the combination of a pen holder having a hollow end, a pen point, a feed bar adapted to fit under the rearward portion of the pen point to form therewith a pen point shank adapted to be inserted into the hollow end of said holder, and a spring element exerting pressure between the inside of the hollow end of the pen holder and said feed bar to removably hold the pen point and feed bar in the holder.

2. In a pen of the class described, the combination of a pen holder having a hollow end, a pen point, a filler bar adapted to fit under the rearward portion of the pen point to form therewith a pen point shank adapted to be inserted into the hollow end of said holder, and a spring element having a stem portion extending into a transverse cavity in said filler bar so as to be secured thereby, and a wing portion extending longitudinally of the bar along its bottom side and exerting pressure against the inside of the hollow end of the pen holder to removably hold the pen point and filler bar in the holder.

3. In a pen of the class described, the combination of a pen holder having a hollow end, a pen point, a feed bar adapted to fit under the rearward portion of the pen point to form therewith a pen point shank adapted to be inserted into the hollow end of the holder, and a metallic spring element carried by said feed bar and exerting pressure on the inside of the hollow end of the pen holder to removably hold the pen point and filler bar in the holder.

4. In a pen of the class described, the combination of a pen holder having a hollow end, a pen point, a feed bar adapted to fit under the pen point, said feed bar having a rearward portion cooperating with the rear-

ward portion of the pen point to form a shank adapted to be inserted into the hollow end of said holder, said pen point and feed bar having interfitting means for longitudinally positioning said parts relative to each other, and a spring element exerting pressure between the inside of the hollow end of the pen holder and said feed bar to removably hold the pen point and feed bar in the holder.

5. In a pen of the class described, the combination of a pen holder having a hollow end, a pen point, a feed bar adapted to fit under the pen point, said feed bar having a rearward portion cooperating with the rearward portion of the pen point to form a shank adapted to be inserted into the hollow end of said holder, said feed bar having an indentation on its upper surface and the pen point having an indentation forming a projection on its under surface adapted to fit into the indentation in said feed bar for longitudinally positioning said parts relative to each other, and a spring element exerting pressure between the inside of the hollow end of the pen holder and said feed bar to removably hold said parts in the holder.

6. In a pen of the class described, the combination of a pen holder having a hollow end, a metallic reinforcing sleeve in said hollow end, a pen point, a feed bar adapted to fit under the pen point, said feed bar having a rearward portion cooperating with the rearward portion of the pen point to form a shank adapted to be inserted into said reinforcing sleeve, and a spring element exerting pressure between the inside of said reinforcing sleeve and said feed bar to removably hold the pen point and feed bar in the holder.

7. In a pen of the class described, the combination of a pen holder having a hollow end, a pen point, a feed bar adapted to fit under the pen point, said feed bar having a rearward portion cooperating with the rearward portion of the pen point to form a shank adapted to be inserted into the hollow end of the said holder, said feed bar having a longitudinally extending groove in its under side, and a spring element secured at its rear end to said feed bar, extending longitudinally thereof in said groove and exerting pressure on the inside of the pen holder to removably hold the pen point and feed bar in the holder.

8. In a pen of the class described, the combination of a pen holder having a hollow end, a pen point, a feed bar adapted to fit under the pen point, said feed bar having a rearward portion cooperating with the rearward portion of the pen point to form a shank adapted to be inserted into the hollow end of the said holder, said pen point and feed bar having interfitting means for longitudinally positioning said parts relative to each other, said feed bar having a longitudinally extend-

ing groove in its under side, and a spring element secured at its rear end to said feed bar, extending longitudinally thereof in said groove and exerting pressure on the inside of the pen holder to removably hold the pen point and feed bar in the holder.

9. A device as defined in claim 2, wherein said filler bar is provided adjacent its forward portion with a plurality of capillary cavities 10 serving to retain and feed ink to said pen point.

GUSTAV J. SENGBUSCH.
